(57) **CLAIM**

I claim the ornamental design for an automobile wheel, as shown and described.

DESCRIPTION

FIG. 1 is a front elevational view of an automobile wheel; and, FIG. 2 is a perspective view thereof.

The broken line showing of the rear portion of the automobile wheel is included for the purpose of illustrating environment and forms no part of the claimed design.

1 Claim, 2 Drawing Sheets**FIG.1**

FIG. 2
